LINE JUSTIFIER FOR KEY OPERATED PRINTING MACHINES

Walter J. Hausman, Washington, D. C., assignor to Burnell Machine Company, Incorporated, Wilmington, Del., a corporation of Delaware

Application September 15, 1938, Serial No. 230,103

10 Claims. (Cl. 197—84)

This invention relates to new and useful improvements in line justifiers for typewriters or other key operated printing machines.

There are, at this time, at least so far as the patented art is concerned, three different methods or modes of operation employed in typewriters, and the like, for obtaining the desired spacing for letters and between words. The most commonly used and what undoubtedly can be considered as the standard method, involves the allotment of uniform spaces between words and for all letters and characters. As the space allotted for all letters and characters as well as between words is determined by the escapement mechanism, this type of machine possesses an escapement which functions to permit movement of the carriage a uniform distance each time a printing key or the spacing bar is operated. Because of the general familiarity with this uniform spacing type of machine, it is unnecessary to refer to any specific patent as an illustration.

In recent years there has been placed on the market a typewriter which is capable of printing with a large number of different styles and sizes of types by interchangeably employing different type plates. To accommodate the different sizes of types, this machine is provided with escapement mechanism which is adjustable to provide two, three or four different width spaces, such as ten, twelve, fourteen or sixteen spaces to the inch, depending upon the model machine being considered. When this machine has its escapement mechanism adjusted or set for any one of the different width spaces, its operation then is the same as that of the aforementioned standard typewriter; i. e., each letter and character is allotted the same space and the spacer bar operates to provide the same space between words as that allotted to each letter or character. Reference may be made to Patent No. 1,964,748, issued to Frank H. Trego, on July 3, 1934, for a complete disclosure of this selectively variable, uniform spacing type of machine.

The third method of spacing involves the allotment of different width spaces for the various letters and characters depending upon the relative widths of the same. This system operates on the principle of providing a certain number of "units" to the inch or to the line and the spaces allotted to the different width letters and characters are multiples of this "unit." For example, such letters as *i*, *j* and *l*, and the characters or punctuation marks ".", ",", and ";", may

be allotted a space corresponding to one "unit"; such letters as *a*, *n*, *b*, and the like may be allotted a space corresponding to two "units"; such letters as *m*, *B*, *L*, and the like, may each be allotted a space corresponding to three "units," etc. It will be appreciated that this designated allotment of different numbers of units to different letters and characters is an arbitrary one and may be varied according to the designers of the various machines employing this "unit" space method. In this type of machine, the spacer bar operates to space words, or the like, two or more "units." The escapement mechanism for this type of machine must, naturally, be capable of allowing the carriage to shift, as the result of operation of each one of the printing keys, or the spacer bar, a distance corresponding to one, two, three or four "units," depending upon the key being actuated. A disclosure of this type of variable or differential spacing machine will be found in the patent numbered 1,286,186, and issued to Monroe E. Miller, on November 26, 1918.

In each one of these three different types of typewriting machines will be found an escapement mechanism which includes a rack or ratchet bar which is operatively connected to the carriage of the machine. The connection between the rack or ratchet bar and the carriage usually is such that the said bar partakes of all longitudinal movements of the carriage. The said bar and the carriage, therefore, are concurrently moved one space or one or more "units" each time a typing key or spacer bar is operated.

In designing a justifying mechanism which is capable of operating, without modification, equally well on all three of the above referred to types of machines, the rack or ratchet bar, which is common to all, is the logical element to place under the control of the justifying mechanism. A proper control of this bar may be had which will not affect or interfere with the intended operations of the different escapement mechanisms by working through the connection between the said bar and the carriage.

It, therefore, is the primary object of this invention to provide line justifying mechanism for key operated printing machines which is capable of being applied to each one of the above referred to types of typewriters or, in fact, to any type of key operated printing machine which has the travel of its carriage controlled by an escapement mechanism which includes a rack or ratchet bar attached to the carriage.

Of course, justification of typed lines to provide a straight or uniform right-hand margin is old in the patented art. In all such justifiers, however, the required justification; i. e., the shortening or lengthening of the lines by one or more spaces or "units," is calculated on the basis of a line of typing, the length of which corresponds to, or substantially to, the full length of the travel of the carriage. The justification takes place throughout the entire length of such a line. Therefore, if an attempt is made to type shorter lines than that for which the machine is designed, full justification does not occur. Furthermore, except for the lines where the same amount of justification is to take place, the first and last characters or letters of the various lines are the only ones which are directly placed underneath or in vertical alignment with each other. This vertical misalignment of the letters and characters throughout the length of the various lines produces a very undesirable appearance and defeats one of the principal purposes of line justification, i. e., simulation of type set printing matter. In type set printing matter, justification is accomplished in a zone of less length than the length of the line being produced but by spacing-out or crowding between words. This type of justification arranges all of the letters and characters for a certain distance at both ends of each line in vertical alignment with each other, and the fact that justification of lines has been resorted to is not so noticeable to the average observer.

Furthermore, in tabulation work such as the pages of price catalogs, it is customary to place at the left-hand side of the page a column of code numbers or characters which identify the various articles. In the center of such a page, there are arranged numerous lines of descriptive matter which describe the articles identified by the code numbers or characters. These lines, of course, are separated so as to be individual to the different code numbers or characters. At the right-hand side of the page there is placed a column containing the sales prices for the various items. The various lines, therefore, will contain numbers at the left- and the right-hand margins and descriptive matter arranged between the numbers. If lines of this character are justified throughout their length, as is necessary with existing justifying mechanisms, the numbers at the left- and right-hand margins of the page will not be vertically aligned.

A further important object of the invention is to provide a line justifying mechanism for key operated printing machines which will accomplish complete justification of each line within a zone located at the center or middle portion of the line, whereby all letters, numbers, or other characters, arranged in the remaining right- and left-hand zones will be positioned in true vertical alignment and lines of different lengths may be typed and fully justified just so the lines are not shorter than the length of the justifying zone.

When pamphlets, or the like, are produced by photo-lithography from compositions of typewritten matter, the typed lines are usually about 7½ inches long. In fact, this is probably the average length for all typed lines. The composition made from the typed material may be enlarged or reduced as desired to produce the proper sized pages in making the photo-lithographic plates. A suitable justifying zone for an average typewritten line, therefore, may be

from 3 to 4 inches in length. It frequently is desirable in producing copies for pamphlets, or the like, to compose a page with a picture arranged on one side or the other and with a narrow column of printed matter positioned at a side of the picture. The lines in such a narrow column naturally are shorter than the lines which extend the full width of the page and may be only 3 or 4 inches long. If a fixed or non-variable justifying zone is provided which is from 3 to 4 inches in length, it would be impossible to justify such short lines and still have end zones of appreciable widths in which the letters and characters are arranged in vertical alignment. Therefore, a justifying zone which is suitable for an average length line will not be suitable for a line which is approximately as short as or shorter than the justifying zone.

It is a still further important object of this invention to provide line justifying mechanism for key operated printing machines by means of which the width of the justifying zone in a given machine may be adjusted or varied at the will of the operator to accommodate typed lines of widely varying lengths.

Another object of the invention is to provide a line justifying mechanism for key operated printing machines which may as readily be applied as an attachment to existing machines as to be built as a permanent part of new machines. In either case, the justifying mechanism will not obstruct or render more difficult the servicing of the printing machine proper.

Other objects and advantages of the invention will be apparent during the course of the following description.

In the accompanying drawings forming a part of this specification and in which like numerals are employed to designate like parts throughout the same.

Figure 1 is a top plan view of a typewriting machine with the line justifying mechanism embodying this invention applied thereto.

Figures 2 and 3 are rear elevational views which collectively disclose the typewriter and line justifying mechanism illustrated in Fig. 1;

Figure 4 is a vertical sectional view taken through the typewriter illustrated in Figs. 1 and 2;

Figure 5 is a detail plan view disclosing the manner in which the line justifying mechanism is operatively connected with the carriage and the rack bar of the escapement mechanism,

Figure 6 is a detail vertical sectional view taken on line 6-6 of Fig. 1,

Figure 7 is a detail vertical sectional view taken on line 7-7 of Fig. 5, and

Figure 8 is a schematic view illustrating the scale markings which appear on the periphery of the dial wheel associated with the setting mechanism of the justifier.

In the drawings, wherein for the purpose of illustration is shown the preferred embodiment of this invention, the line justifying mechanism embodying this invention has been applied to the selectively variable, uniform spacing type of machine fully disclosed in the above referred to Trego Patent No. 1,964,748. Reference may be had to this patent for any detail features of the typewriter which are not fully illustrated or described herein.

The typewriter machine includes a main frame 10 to which is secured a track 11 upon which is mounted a carriage 12 for travel back and forth transversely of the machine. The carriage is pro-

vided with a bar 13 which cooperates with the track 11 through anti-friction balls 14 to guide the carriage. The carriage is further guided by a bar 15 at its upper end.

5 The carriage 12, see Fig. 2, is urged in a letter feeding direction by a spring drum 16 which is rotatably supported on the machine frame 10 and is connected to the carriage by a strap or draw band 17. Letter feeding movements of the 10 carriage are effected upon actuation of the various letter and character printing keys, not shown, and these movements are controlled by escapement mechanism disclosed in Figs. 1, 2 and 4 and designated generally by the reference character 15 18.

The escapement mechanism includes a pinion element 19, see Figs. 1 and 4, which is slidably supported on a shaft 20. The pinion element embodies three pinions 21, 22 and 23 of different 20 diameters to effect variable spacing of the carriage by being selectively placed in engagement with a rack bar 24. This rack bar is vertically swingably connected to the carriage 12 by means of the arms 25 which are mounted on the opposite ends of the carriage. To effect shifting of the rack bar 24 into mesh with either one of the different diametered pinions 21, 22 or 23, the rack bar must be elevated to disengage it from one pinion and the pinion element 19 must then be 30 shifted along the shaft 20 to place the selected pinion beneath the rack bar. This is accomplished in the following manner:

Fig. 1 discloses a lever 26 which is suitably pivotally mounted on the right-hand side of the 35 main frame 10 and partakes of vertical movement. The free end of this lever is provided with a series of teeth 27 which are placed in engagement with the teeth of the rack bar 24 when this lever is pivoted upwardly from its normal 40 position. The pivoting of the lever performs the dual function of elevating the rack bar 24 out of engagement with one of the pinions and holding the carriage against movement in response to the spring drum 16 by the engagement of the teeth 45 27 with the teeth of the rack bar.

To accomplish raising and lowering of the lever 26 and shifting of the pinion element 19 axially of the shaft 20, a finger piece 28 is rigidly secured to a shaft 29 which is journaled in bearing lugs 50 30 and 31 formed on the main frame 10. The shaft 29 is capable of being rocked and shifted axially by the finger piece 28. This rocking and shifting axially of the shaft 29 is accompanied by movement of the finger piece 28 into and out of the various slots 32, 33 and 34 formed in the guide plate 35. Fig. 1 discloses indicia "10," "12," and "16" which indicate the number of spaces to the inch which will be provided by each one of the three pinions 21, 22 and 23 when the rack bar 24 55 is meshing therewith. It will be appreciated that these pinions vary in diameter and are of the same pitch as the rack bar 24. They also vary in size respectively according to the number of teeth. Accordingly, for each movement of the 60 escapement wheel, which will be described at a later point and which is constant, the angular distance of actuation of the pinions is the same, but the linear distance which the rack may be fed by the various pinions increases as the diameters of 65 the pinions increase.

Fig. 1 discloses the shaft 29 as being pivotally and rotatably connected at 36 to a lever 37 which is pivoted to a suitable portion of the main frame 10 at 38 and is provided with a forked end 39 provided with diametrically opposite fingers received

in the grooved flange 40 which forms an integral part of the pinion element 19. Axial shifting movement of the shaft 29, therefore, results in axial movement of the pinion element 19 relative to the rack bar 24. Keyed to the shaft 29 is an arm 41, see Figs. 1 and 4, which underlies the lever 26 and functions to raise this lever as the shaft 29 is rocked. The extremity of the arm 41 is shaped to underlie the lever 26 during all axial shifting movements of the shaft 29 to which the 10 arm is keyed.

Fig. 4 discloses the rack bar 24 meshing with the intermediate pinion 22. When in this position, the finger-piece 28 will occupy the slot 33, as shown in Fig. 1. If it is desired to shift the 15 pinion element 19 so that the rack bar will mesh with the teeth of the pinion 23, the finger-piece 28 is moved out of the intermediate slot 33 into the communicating slot 42 of the guide plate 35 and then is moved longitudinally of the slot 42 20 until it registers with the slot 32, whereupon the finger-piece 28 is shifted into this latter slot. This movement of the finger-piece has first caused the shaft 29 to rock, thereby swinging the lever 41 upwardly to raise the lever 26 into engagement with the rack bar 24 for elevating the teeth of this bar out of mesh with the pinion 22. The longitudinal movement of the finger-piece 28 through the communicating slot 42 has caused axial movement of the shaft 29 which results in 30 pivotal movement of the forked lever 37. This movement of the lever shifts the pinion element 19 into a position where the largest pinion 23 underlies the rack bar 24. When the finger-piece 28 is moved into the slot 32, the rack bar is lowered into engagement with the larger pinion 23. Reverse movement of the pinion element 19 to cause the smallest pinion 21 to mesh with the rack bar 24 will be understood from the above 35 description.

The pinion element 19 is suitably connected to the shaft 20, in a manner not disclosed, so as to cause this shaft to rotate with the pinion element. An escapement wheel 43, see Figs. 1, 2 and 4, is rigidly connected to the shaft 20 for rotary movement with this shaft. It will be appreciated, therefore, that the carriage 12 is under the influence of the spring drum 16 which constantly tends to rotate the escapement shaft 20 through the medium of the rack bar 24, the pinion element 45 19, and the connection, not shown, between this pinion element and the escapement shaft 20.

The escapement wheel 43 is normally held against rotation by a loose dog 44, see Fig. 2, pivoted on a stud 45 carried by an arm 46. This 50 arm 46 is supported at one end on the escapement shaft 20 and at its other end by the mounting 47. Pivoted at 48 is a rockable escapement lever or dog 49 which has at one end an arm 50 engageable with a type key actuating arm 51. It will 55 be understood that whenever a type key is depressed, the arm 51 is moved downwardly to rock the escapement lever or dog 49. The spring 52 functions to normally retain the escapement lever or dog 49 in the position best illustrated in Fig. 2. 60 The rockable escapement lever or dog 49 is provided with a slot 53 in an upstanding arm of the same into which projects a pin 54 carried by the loose dog 44. This pin and slot connection results in swinging the dog 44 out of engagement 65 with the escapement wheel 43 when the escapement lever or dog 49 is rocked about its pivot 48. A fixed dog 55 is secured to the escapement lever or dog 49 and is brought into the path of the teeth of said escapement wheel 43 before the said 70 75

wheel is released from the loose dog 44. The loose dog 44 is then carried upwardly past the previously engaged tooth of the escapement wheel. This upward movement of the loose dog is effected by the movement of a printing hammer 56, the details of which are not disclosed. It is to be understood, however, that in the Trego machine, the impression on the paper, or the like, is made by the forcing of the paper against the printing type by means of a power operated printing hammer which is represented at 56. Upon releasing of the depressed printing key, the arm 51 is returned to normal, thus permitting the escapement lever or dog 49 to return to its normal position. The loose dog 44 is thus swung back, by the escapement lever or dog 49, into the path of the next succeeding tooth of the escapement wheel, and the fixed dog 55 is carried out of engagement with the escapement wheel thus permitting the completion of the letter spacing movement of the carriage.

There has now been explained enough of the Trego machine to constitute a disclosure of a carriage which is powered for letter spacing movement by a spring drum and which is controlled by an escapement mechanism, including a rack bar to bring about letter spacing movement of the carriage. The escapement mechanism includes shiftable or variable pinion and rack mechanism by means of which the carriage is permitted to shift to provide either ten, twelve or sixteen spaces to the inch.

To accomplish justification of lines typed on this machine, it becomes desirable to shorten or lengthen the respective lines 1, 2 or more spaces. This justification must be accomplished regardless of whether the escapement mechanism is set for ten, twelve or sixteen spaces to the inch. Incidentally, it will be appreciated that by providing a greater or lesser number of different sized pinions for the pinion element, a different combination or variation of spacings to the inch may be provided. To determine how many spaces the various lines of a typed page must be lengthened or shortened, the material to be justified is first typed and in preparing this original copy, the right-hand margin is made as straight or uniform as is possible. The justifying mechanism which is disclosed and described herein is capable of justifying a total of eight spaces to the line which has been determined to be ample justification to take care of all conditions. It will be appreciated, however, that the mechanism may be designed to justify a greater or lesser number of spaces if desired. The eight space justification made possible with this mechanism is divided up into a normal or neutral space, two spaces through which a line can be shortened and five spaces through which a line can be lengthened. The right-hand marginal portion of the first copy of the material to be justified, therefore, is marked off in vertical columns so as to provide a normal or neutral column in which all of the justified lines will terminate. This neutral column must be arranged so that no line of the original or first copy will have any letters or characters which extend more than two spaces therebeyond. When the right-hand marginal portion of the first or original copy is ruled or laid off in this manner, it is a very simple matter to determine whether each one of the several lines requires any justification and whether the justification must consist of shortening or lengthening the line and to what extent each line must be justified. From this ruled off or scaled original

copy, the operator will make the desired justified copy.

With the ordinary typewriter, the rack bar is made in one piece and is connected to the carriage in a manner to prevent relative longitudinal movement between the rack bar and the carriage. With this justifying mechanism, a special form of rack bar is substituted for the conventional bar. This special bar is illustrated in Figs. 2, 4 and 5 as consisting of an upper section 57 which is rigidly connected to the previously described end mounting arms 25. This upper bar member 57 is provided with two, or more, longitudinally extending, spaced slots 58. Underlying the upper rack bar section is a lower section 59 which is provided with teeth to mesh with the respective pinions 21, 22 and 23. This lower rack bar section 59 floats or slides relative to the upper rack bar section or longitudinally of the carriage 12. To allow for this floating movement, a screw 60 passes through one of the slots 58 and is threadedly connected to the lower rack bar section 59. A screw 61 with an apertured head passes through the remaining slot 58 and is threaded or otherwise connected at its lower end to the toothed rack bar section 59. These two screws 60 and 61 will hold the lower rack bar section 59 in longitudinal alignment with the upper rack bar section, but will permit the desired floating movement of the toothed rack bar section.

Rigidly secured to the outer side of the rack supporting arm 25 located at the left-hand end of the carriage 12 is an angle bracket 62. This bracket acts as a support for a bell crank lever 63 which is pivotally mounted to the bracket 62 by means of the pivot pin or bolt 64. The bell crank lever 63 is formed of two relatively adjustable sections. The main section 65 takes the form of an elongated arm having a follower roller 66 journaled on and depending from its extremity. Extending along one side edge of the arm 65 is a guide channel 67 which functions in a manner to be described at a later point. The second section or part of the bell crank lever 63 consists of an angular arm 68 through which the pivot pin 64 passes. This angle arm 68 is adjustably connected to the arm 65 by means of a set screw 69 which is threaded into the arm 65 and passes through an arcuate slot 70 formed in the arm 68. By loosening the screw 69, the arms 65 and 68 may be angularly adjusted relative to each other. The arm 68 is provided with an upstanding branch or flange 71 through which passes a pin 72. This pin 72 passes through one member 73 of a swivel connection which further includes a block 74. This block is connected to a link 75 which extends to and passes through the eye of the screw 61 previously described as being connected to the toothed rack section 59. Due to this mechanism which has just been described, it will be appreciated that pivotal movement of the bell crank lever 63 will result in longitudinal movement of the rack bar section 59 relative to its upper section 57 and the carriage 12. A coil spring 76 is connected to the pin 72 at one end and to a portion of the carriage 12 at its remaining end to spring bias the pin, the bell crank lever, and the rack bar in one direction. Supplementing the action of the spring 76 is a leaf spring 77 which is connected to the mounting bracket 62 at one end and bears against the upper swivel element 73 at a point adjacent its free end.

As has been explained above, the escapement mechanism 18 will function as a result of actu-

ation of the various type keys to bring about letter spacing movement of the carriage with the letter spacing movement amounting to ten, twelve, sixteen, or the like, spaces to the inch. 5 If the bell crank lever 63 is held in a normal or neutral position during this letter spacing movement of the carriage, the two sections 57 and 59 of the rack bar will move concurrently with the carriage. If, however, the bell crank 10 lever 63 is caused to pivot or swing as a result of movement of the carriage, the lower section 59 of the rack bar will be caused to move relative to the carriage. This lower rack bar section 59 always responds to the movement produced by 15 the escapement mechanism 18. If the bell crank lever 63 is caused to move or swing in one direction as a result of movement of the carriage, the carriage will be restrained from moving to the same extent as the lower rack bar section 59. 20 If the bell crank lever 63 is caused to move or swing in the opposite direction as a result of letter spacing travel of the carriage, the carriage will be moved to a greater extent or for a greater distance than the movement of the lower 25 rack bar section 59. The bell crank lever 63, therefore, can be moved relative to the carriage to produce a greater or lesser movement of the carriage than the movement of the toothed lower section of the rack bar. In this way, the lines 30 to be typed may be lengthened or shortened as desired.

To bring about this desired movement of the bell crank lever 63 relative to the carriage 12 during letter spacing travel of this carriage, the 35 follower roller 66 is caused to travel along one surface of a cam rail which is designated in its entirety by the reference character 78 and which extends lengthwise of the direction of travel of the carriage. This cam rail is made up of an 40 inner section 79 which is longitudinally adjustably connected by the screws 80 and slots 80' (see Figs. 1 and 3) to a part of the main frame 10, an intermediate section 81, and an outer end section 82. The adjacent ends of these three sections 45 are pivotally connected together by the pins 83.

To support the intermediate and outer sections of the cam rail as well as the manual adjusting mechanism for the cam rail, a frame 84 is secured by screws, or the like, 85 to the left-hand 50 end of the typewriter main frame 10. A brace member 86 bridges the frame 84 in parallelism with the outer side bar 87 of said frame. A short brace bar 88 is connected at its ends to the brace 55 86 and the outer frame bar 87 and supports a vertical plate 89 which is arranged in parallelism with the rear part 90 of the frame 84. Two parallel guide bars 91 are supported by the frame part 90 and the vertical plate 89. These guide bars are arranged at right angles to the direction 60 of travel of the carriage 12. In Figs. 3 and 6, there is disclosed a slide block 92 supported on the rails or rods 91. The outer cam rail section 82 is provided with a longitudinally extending slot 93 in which is slidably positioned a block 94 65 which is secured to the slide block 92 by a pair of screws, or the like, 95. This type of connection between the slide block 92 and the outer cam rail section 82 permits the cam rail section to move forwardly and rearwardly with the block 92 and relative to the rails or rods 91 and to move transversely of these rails or rods or so that the auxiliary slide block 94 will partake of longitudinal movement relative to the elongated longitudinal slot 93 formed in the outer cam rail 70 section 82. This transverse movement results

from the operation of certain control mechanism to be described in detail at a later point.

To bring about movement of the slide block 92 and outer cam rail section longitudinally of the rails or rods 91, a strap 96 is connected at its inner end to this slide block 92 and extends to the front of the frame 84 and through a guide plate 97 which is suitably secured to the front bar of this frame 84. The upper surface of the strap 96 is provided with a series of teeth to 10 form a rack bar 98 which extends longitudinally of the strap.

This rack bar meshes with a pinion 99 which is mounted on a shaft 100 journaled in bearing brackets 101 which are secured to the front rail 15 of the frame 84. An operating knob 102 is fastened to the shaft 100 for rotating this shaft and its pinion 99 to bring about longitudinal movement of the strap 96.

In Fig. 1 the cam rail 78 is illustrated with its 20 various sections 79, 81, and 82 in longitudinal alignment with each other. This is the normal or neutral position of the various cam rail sections. When the several sections are thus arranged, the carriage 12 may move throughout its 25 entire range of travel without the bell crank lever 63 being caused to pivot relative to the carriage. The carriage, therefore, will partake of the same movements as the toothed section 59 of the rack bar. By rotating the shaft 100 in either direction, the strap 96 will be moved longitudinally for shifting the outer cam rail section 82 along the rods 91. These rods maintain the outer cam rail section in parallelism with the path of travel of the carriage regardless of the position 30 assumed by this cam rail section.

The manner of connecting the inner cam rail section to the typewriter frame 10 also maintains this section 79 in parallelism with the path of travel of the carriage although the slots 80' permit this inner section to move longitudinally. Movement of the outer cam rail section 82 along the rods 91 will cause the intermediate cam rail section 81 to assume an angular position relative to the path of travel of the carriage. Rotation 40 of the shaft 100 to cause the strap 96 to move longitudinally inwardly will cause the intermediate cam rail section 81 to assume an angular position extending rearwardly of the path of travel of the carriage. The bell crank lever 63, 50 therefore, will partake of a pivotal movement in a clockwise direction, when viewed from above, while its follower roller 66 travels lengthwise of the intermediate cam rail section 81. This clockwise swinging movement of the bell crank lever 63 will result in causing the carriage 12 to move a greater distance than the movement of the toothed rack bar section 59. Due to this increased movement of the carriage, the line being typed will be expanded or stretched out. If the shaft 60 100 is rotated in the opposite direction to cause the outer cam rail section 82 to be moved toward the front of the frame 84 relative to its neutral position (see Fig. 1), the intermediate cam rail section 81 will assume an angular position opposite to the one described above or a position in which it extends toward the front of the frame 84. When the bell crank lever follower roll 66 travels over the intermediate cam rail section 81 when the latter is in the angular position 70 just described, the bell crank lever 63 will be caused to partake of pivotal movement in a counterclockwise direction, when viewed from above, as the carriage partakes of letter spacing movement. This counterclockwise swinging 75

movement of the bell crank lever will retard the movement of the carriage 12 relative to the movement of the toothed rack bar section 59; i. e., the carriage 12 will not move to the same extent as the toothed rack bar section, and the typed line will be shortened. As the intermediate is caused to assume different angular positions relative to the inner and outer sections, the overall length of the three sections varies, 10 and this variation is taken care of by the slots 80'.

It will be appreciated that the greater the angularity of the intermediate cam rail section 81, the greater the swinging or pivotal movement of the bell crank lever 63 and the greater the 15 justification of the line being typed. Therefore, it becomes necessary to be able to determine to what extent the intermediate cam rail section 81 should be adjusted to expand or contract the line to be typed one, two or more spaces. This 20 desired degree of adjustment of the intermediate cam rail section, naturally, varies depending upon the adjustment of the escapement mechanism to provide different numbers of spaces per inch. To enable the operator to accurately determine the desired adjustment of the intermediate cam rail section, a dial wheel 103 is secured to the shaft 100. A sight gauge plate 104 is arranged in the manner illustrated in Figs. 1 and 6 so that its free edge overlies the periphery of 30 the dial wheel. Fig. 8 discloses the scale markings which appear on the periphery of this dial wheel. It will be noted that this figure discloses four peripheral columns of scale readings. The typewriter previously described is capable of being adjusted for ten, twelve and sixteen spaces 35 per inch. Certain models of this type of typewriter are capable of being adjusted to provide ten, twelve, fourteen and sixteen spaces to the inch. The dial wheel 103, therefore, has four peripheral columns to receive scale designations for 40 these four different typewriter settings. The columns for the ten, twelve and sixteen spaces to the inch, however, are the only columns to which scale designations have been applied. It 45 will be noted in Fig. 8 that each column has a line marked "N" and that these lines are in alignment with each other transversely of the dial wheel periphery. These lines "N" all register with the sight gauge edge of the member 104 50 in Fig. 1. When the dial wheel 103 is in this position, the three cam rail sections 79, 81 and 82 are in longitudinal alignment with each other and the carriage will partake of the same movements as the lower toothed section 59 of the 55 rack bar. All of the scale lines appearing above the "N" lines in Fig. 8 are provided with plus readings. By adjusting the dial wheel 103, so that the proper plus number registers with the free edge of the sight gauge 104, the line being 60 typed will be expanded the number of spaces designated. Fig. 8 also discloses each column as having two lines below the "N" lines which bear minus numbers. By setting the dial wheel 103, so that one of these minus numbers registers with the sight or gauge edge of the member 104, the line being typed will be reduced in length the 65 number of spaces designated. Of course, when the typewriter is set for ten spaces to the inch, the column of numbers which registers with the number 10 on the free edge of the gauge 104 should be employed. The remaining two columns register with the numbers 12 and 16 appearing on the gauge 104. These two columns should be 70 employed when the typewriter is set in a condi- 75

tion to provide either twelve or sixteen spaces to the inch.

As has been noted above, the two end sections 79 and 82 of the cam rail are always arranged in parallelism with the path of travel of the carriage. Engagement of the bell crank lever follower roller 66 with these two end sections, therefore, will not provide any justification of the line being typed. Justification only occurs when the follower roller 66 of the bell crank lever 63 is in engagement with the intermediate cam rail section 81. The bell crank lever follower is caused to travel over the adjustable intermediate cam rail section 81 while the typewriter is operating to print the intermediate or central zone of a line. With the paper receiving the printing matter properly positioned in the carriage, this justifying zone will be arranged in the middle of the page so that a typed line of average length will have a justified center zone and a normally spaced zone at each end of the justifying zone.

As has been noted above, it may become desirable to justify lines which are only three or four inches long. A justifying zone of proper length to take care of an average line, which will be in the neighborhood of 7½ inches long, will not be suitable for justifying a much shorter line. To take care of this condition, the drawings illustrate the central or intermediate cam rail section 81 as being adjustable in length. This intermediate cam rail section is provided with overlapped parts 105 and 106. The upper part 105 is provided with two longitudinally extending slots 107. Screws 108 and 108' pass through these slots and are threaded into the lower part 106. By loosening the screw 108' which has the knurled head, the parts 105 and 106 may be shifted longitudinally relative to each other to lengthen and shorten the intermediate cam rail section. The screw 108 is left loose enough so that it only acts as a guide. The extent of adjustability of this intermediate cam rail section, of course, is only limited by the length of the slots 107.

To accomplish adjustment of the section 81, the auxiliary slide block 94 has secured thereto an upstanding block 109 provided with an internally threaded opening 110 in which is threaded the screw 111. The outer end portion of this screw is journaled in a bracket 112 fastened to the end of the outer cam rail section 82. A pin 113 passes through the screw 111 and is positioned in a slot 114 formed in the bracket 112 and functions to hold the screw against longitudinal movement. A knurled knob 115 is fastened to the end of the screw and is employed by the operator to effect rotation of the screw.

When the length of the cam rail section 81 is to be changed, the operator loosens the screw 108' and turns the screw 111 in the proper direction. Rotation of this screw 111 brings about longitudinal movement of the outer cam rail section 82 relative to the auxiliary slide block 94. After the length of the intermediate cam rail section has been changed as desired, the screw 108' is tightened down to clamp the two parts 105 and 106, and the justifying mechanism is again ready for use. Any suitable scale or gauge may be employed in connection with the parts 105 and 106 to indicate adjustments of the same.

From the above description, it will be appreciated that lines typed on this machine may be lengthened and shortened to the extent of eight spaces and that justification will take place only in the central or intermediate portion of a line.

The letters, numbers, and characters appearing at the end zones of the lines, therefore, will be in vertical alignment with each other. The justification of lines by this machine, therefore, will approximate the type of justification provided for in type set printing.

It is to be understood that the form of this invention herewith shown and described is to be taken as a preferred example of the same and that various changes in the shape, size, and arrangement of parts may be resorted to without departing from the spirit of the invention or the scope of the subjoined claims.

Having thus described the invention, I claim:

1. In a key operated printing machine, a traveling carriage, escapement mechanism including a bar which is advanced step by step in response to actuation of the printing keys, a cam controlled element movably mounted on the carriage, means for connecting said element to said bar to cause movements of said element to effect relative longitudinal adjustments between the carriage and the bar, a cam for controlling the movements of said element having an active surface which is divided into relatively adjustable sections, and means for adjusting said sections relative to each other to cause the controlling action of one of said sections to effect movement of the element while the controlling actions of the remaining sections result in retaining said element against movement.

2. In a key operated printing machine, a traveling carriage, escapement mechanism including a bar which is advanced step by step in response to actuation of the printing keys, a cam controlled element movably mounted on the carriage, means for connecting said element to said bar to cause movements of said element to effect relative longitudinal adjustments between the carriage and the bar, a cam for controlling the movements of said element having an active surface which is divided into relatively adjustable sections, and means for variably adjusting said sections relative to each other to cause the controlling action of one of said sections to effect different degrees of movement of the element while the controlling actions of the remaining sections result in retaining said element against movement.

3. In a key operated printing machine, a traveling carriage, escapement mechanism including a bar which is advanced step by step in response to actuation of the printing keys, a cam controlled element movably mounted on the carriage, means for connecting said element to said bar to cause movements of said element to effect relative longitudinal adjustments between the carriage and the bar, a cam for controlling the movements of said element having an active surface which is divided into relatively adjustable sections, and means for adjusting said sections relative to each other to cause the controlling action of one of said sections to effect movement of the element while the controlling actions of the remaining sections result in retaining said element against movement, and means for varying the active length of the cam surface section which effects movement of said element.

4. In a key operated printing machine, a traveling carriage, escapement mechanism including a bar which is advanced step by step in response to actuation of the printing keys, a cam controlled element movably mounted on the carriage, means for connecting said element to said bar to cause movements of said element to

effect relative longitudinal adjustments between the carriage and the bar, a cam for controlling the movements of said element having an active surface which is divided into relatively adjustable sections, means for variably adjusting said sections relative to each other to cause the controlling action of one of said sections to effect different degrees of movement of the element while the controlling actions of the remaining sections result in retaining said element against movement, and means for varying the active length of the cam surface section which effects movement of said element.

5. In a key operated printing machine, a traveling carriage, escapement mechanism including a bar which is advanced step by step in response to actuation of the printing keys, a bell crank lever pivotally mounted on the carriage, a link connecting one arm of the lever to said bar to cause movements of the lever to effect relative longitudinal adjustments between the carriage and said bar, a sectional cam rail arranged lengthwise of the direction of travel of the carriage, a rail follower mounted on the remaining end of said bell crank lever, and means for adjusting said cam rail sections relative to each other so that one of said sections will be angularly arranged relative to the direction of travel of said carriage to cause pivotal movement of the bell crank lever as its follower travels over said section and so that the remaining sections will be arranged in parallelism with said direction of travel so as to retain said bell crank lever against pivotal movement while its follower travels thereover.

6. In a key operated printing machine, a traveling carriage, escapement mechanism including a bar which is advanced step by step in response to actuation of the printing keys, a bell crank lever pivotally mounted on the carriage, a link connecting one arm of the lever to said bar to cause movements of the lever to effect relative longitudinal adjustments between the carriage and said bar, a sectional cam rail arranged lengthwise of the direction of travel of the carriage, a rail follower mounted on the remaining end of said bell crank lever, and means for adjusting said cam rail sections relative to each other so that the middle section will lie in a vertical plane which is angularly arranged relative to the plane in which the carriage travels while the remaining sections will lie in planes parallel to each other and the plane in which the carriage travels, said angularly arranged section causing pivotal movement of the bell crank lever as its follower travels thereover while said remaining sections function to retain said bell crank lever against pivotal movement.

7. In a key operated printing machine, a traveling carriage, escapement mechanism including a bar which is advanced step by step in response to actuation of the printing keys, a bell crank lever pivotally mounted on the carriage, a link connecting one arm of the lever to said bar to cause movements of the lever to effect relative longitudinal adjustments between the carriage and said bar, a sectional cam rail arranged lengthwise of the direction of travel of the carriage, a rail follower mounted on the remaining end of said bell crank lever, and means for adjusting said cam rail sections relative to each other to selectively arrange one of said sections at different angular positions relative to the direction of travel of said carriage to cause pivotal movement of the bell crank lever as its follower

- travels over said section and to arrange the remaining sections in parallelism with said direction of travel so as to retain said bell crank lever against pivotal movement while its follower travels thereover. 5
8. In a key operated printing machine, a traveling carriage, escapement mechanism including a bar which is advanced step by step in response to actuation of the printing keys, a bell 10 crank lever pivotally mounted on the carriage, a link connecting one arm of the lever to said bar to cause movements of the lever to effect relative longitudinal adjustments between the carriage and said bar, a sectional cam rail arranged 15 lengthwise of the direction of travel of the carriage, a rail follower mounted on the remaining end of said bell crank lever, and means for adjusting said cam rail sections relative to each other so that one of said sections will be angularly 20 arranged relative to the direction of travel of said carriage to cause pivotal movement of the bell crank lever as its follower travels over said section and so that the remaining sections will be arranged in parallelism with said direction 25 of travel so as to retain said bell crank lever against pivotal movement while its follower travels thereover, and means for varying the length of the rail section which may be angularly arranged. 30
9. In a key operated printing machine, a traveling carriage, escapement mechanism including a bar which is advanced step by step in response to actuation of the printing keys, a bell crank lever pivotally mounted on the carriage, a link connecting one arm of the lever to said bar to cause movements of the lever to effect relative longitudinal adjustments between the carriage and said bar, a sectional cam rail arranged 35 lengthwise of the direction of travel of the carriage, a rail follower mounted on the remaining end of said bell crank lever, and means for adjusting said cam rail sections relative to each other so that the middle section will lie in 40
- a vertical plane which is angularly arranged relative to the plane in which the carriage travels while the remaining sections will lie in planes parallel to each other and the plane in which the carriage travels, said angularly arranged section causing pivotal movement of the bell crank lever as its follower travels thereover while said remaining sections function to retain said bell crank lever against pivotal movement, and means for varying the length of the middle rail section. 5
10. A justifying attachment for conventional key operated printing machines comprising a two-part rack bar to be substituted for the usual one-piece rack bar of the printing machine, means for mounting one of said rack bar parts 10 on the machine carriage to move therewith, means for mounting the other part, which includes the rack teeth, on the first part for movement longitudinally thereof, a mounting bracket 15 means for attaching it to one end of the machine carriage to move therewith, a cam controlled element movably mounted on said bracket, means for connecting said element to the movable part of the rack bar to cause movement of the element to effect movement of said 20 rack bar part relative to its supporting bar part, an attachment frame having means for mounting the same and arranging it so as to project from an end of the main frame of the printing machine, a cam for controlling the movement of 25 said element, as the element travels with the machine carriage, overlying and supported on said attachment frame, said cam having an active surface which is divided into relatively adjustable sections, and means mounted on said 30 attachment frame for effecting adjustment of said sections relative to each other to cause the controlling action of one of said sections to effect movement of the element while the controlling actions of the remaining sections result in retaining said element against movement. 35

WALTER J. HAUSMAN.
